CLAIM

The ornamental design for a cellular phone, as shown and described.

DESCRIPTION

FIG. 1 is a front elevational view of a cellular phone showing our new design with the lid in a closed position;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a front, side perspective view thereof;
FIG. 8 is a front, side perspective view of a cellular phone showing our new design with the lid in an open position;
FIG. 9 is a front elevational view thereof;
FIG. 10 is a rear elevational view thereof;
FIG. 11 is a left side elevational view thereof;
FIG. 12 is a right side elevational view thereof;
FIG. 13 is a top plan view thereof; and,
FIG. 14 is a bottom plan view thereof.

The broken lines showing the outline of a keypad is for illustration purposes only and forms no part of the claimed invention.
